(57) **CLAIM**

The ornamental design for a sample preparation instrument, as shown and described.

DESCRIPTION

FIG. 1 is a perspective view of a sample preparation instrument in accordance with the present invention.

FIG. 2 is a front view of the sample preparation instrument of FIG. 1.

FIG. 3 is a rear view of the sample preparation instrument of FIG. 1.

FIG. 4 is a right side view of the sample preparation instrument of FIG. 1.

FIG. 5 is a left side view of the sample preparation instrument of FIG. 1.

FIG. 6 is a top view of the sample preparation instrument of FIG. 1; and,

FIG. 7 is a bottom view of the sample preparation instrument of FIG. 1.

In the drawings, broken lines depict portions of the sample preparation instrument that form no part of the claimed design.
